(57) **CLAIM**

The ornamental design for a neck warmer, as shown and described.

DESCRIPTION

FIG. 1 is a perspective top front right view of a neck warmer, showing my new design;

FIG. 2 is a perspective top rear left view thereof;

FIG. 3 is a front elevation view thereof;

FIG. 4 is a rear elevation view thereof;

FIG. 5 is a left elevation view thereof, with a right elevation view being identical; and,

FIG. 6 is a top plan view thereof, with a bottom plan view being identical.

The broken lines represent the boundary area of an unclaimed attachment mechanism and form no part of the claimed design.
